UNITED STATES PATENT OFFICE

ARTHUR M. LOWENTHAL, OF ROCHESTER, NEW YORK, ASSIGNOR TO MAX LOWENTHAL & SONS, A COPARTNERSHIP CONSISTING OF HARRY M. LOWENTHAL, EUGENE M. LOWENTHAL, AND ARTHUR M. LOWENTHAL

SWEATER

Application filed December 14, 1927. Serial No. 240,029.

The present invention relates to sweaters and an object thereof is to provide a knitted sweater which may be used with an open neck and a closed neck and which will have a neat 5 appearance when used either way. Another object of the invention is to provide a sweater with knitted lapels, the free edges of which are selvaged. Still another object of the invention is to provide a sweater having lapels 10 separate from the body of the garment provided with portions extending along the shoulder seam to and stitched to the sleeves of the sweater.

To these and other ends, the invention consists of certain parts and combinations of parts, all of which will be hereinafter described: the novel features being pointed out in the appended claims.

In the drawings:

20 Fig. 1 is a front view of the sweater with the lapels in open positions;

Fig. 2 is a fragmentary front view showing one of the lapels open and the other closed;

25 Fig. 3 is a fragmentary front view showing the two lapels closed;

Fig. 4 is a rear view of the upper portion of the sweater;

30 Fig. 5 is a detail view showing the two knitted lapels and the knitted back strip removed from the sweater; and

35 Fig. 6 is a diagrammatic view showing the manner in which the lapels are formed from a single strip of knitting with a minimum of wastage.

Referring to the illustrated embodiment of the invention, the body of the sweater comprises a front 1, and a back 2 formed, in this instance, by tubular knitting of any desired 40 stitch and having sleeves 3 stitched thereto at 4.

In an application filed by me on December 14, 1927, Serial No. 240,028, I have disclosed and claimed a strip 5 formed of a separately 45 knitted strip having selvaged side edges with one side edge 6 stitched to the back portion 2 of the garment and its ends stitched at 7 to the sleeves 3, the upper edge of this strip being situated at the shoulder seam 7 of the garment. It is preferred to use this back

piece with the present invention, although the invention is not limited to such use.

The front of the body of the sweater has a neck recess formed, in this instance, by cutting away two downwardly converging edges 55 8 which intersect the vertical walls 9 of a notch at the center of the neck recess, the upper portion of the front of the body 1 being cut on horizontal lines 10 leading from the upper ends of the converging walls 8 to the 60 shoulder seam and spaced from the shoulder seam. To the edges of the neck recess the lapels are secured.

The lapels are of novel construction and are 65 preferably knitted. A novel method of knitting these lapels consists in the making of a zigzag knitted strip such as shown in Fig. 6. This strip is formed by providing longitudinal rows 11 of knitting arranged end to end and at angles to each other. The method of 70 forming these longitudinal rows at angles to each other is well known to a skilled knitter, and may be accomplished by the racking of the knitting machine. For instance, the rows 11 may be either full or half cardigan racked 75 while the portion 12 between them will be half racked if the rows are full racked, or full racked if the rows are half racked, the angular direction being determined by the direction in which the racking takes place. 80

The strip thus produced is then cut on the black lines, Fig. 6 so as to provide the plurality of lapels, with the small pieces 13 as waste. This produces a plurality of lapels 85 each having two angularly arranged portions, each portion having longitudinal rows of stitches at an angle to the other end of like racking, say full cardigan racking, separated at 12 by a different type of racking, say half cardigan racking, each lapel being wider at 90 the angle between the two sets of rows of knitting. Each lapel also has a selvaged free edge extending from its point or corner.

The lower ends of each lapel are stitched 95 to the bottom of the lower central notched portion of the neck recess and each are also stitched along one side to the vertical edge 9 of the central notched portion of the neck recess. The edge of the wide portion of the lapel is stitched to one of the converging 100

sides 8 of the neck recess while the lower horizontal edge of the horizontal portion of each lapel is stitched at 15 to the upper edge of the body portion. The upper horizontal edge of the horizontal portion has a portion thereof stitched to the back strip 5 so as to form, with the back piece 5, the shoulder seam 7, while the end of the horizontal portion of the lapel is stitched at 14 to a sleeve 3.

10 It will thus be seen that the lapels will have their vertical portions arranged one overlapping the other when the garment is closed as shown in Fig. 3, and yet the lapels may be thrown back to provide an open garment as shown in Fig. 1. The vertical edge of each lapel is selvaged as is also the horizontal edge so that the selvage edges on the lapels and the selvage edge on the back strip 5 meet at the shoulder seam, thus preventing 15 unravelling at this point. Furthermore the lapels, by extending to the sleeve seams are materially strengthened at their upper edges and strains or pulls on the lapels are transmitted to the sleeve seams instead of being 20 imparted to the free stretching body of the sweater. Each lapel may be provided with a button hole 17 so that buttons 16 may be used for holding the lapels in open position. A button 18 on the undermost lapel may be 25 employed for fitting in the button hole 17 on the outermost lapel to make a closed garment. It will be understood that the invention is not limited to extending the lapels to the sleeves.

30 What I claim as my invention and desire to secure by Letters Patent is:

1. A sweater comprising a body having a front formed with a neck recess, sleeves stitched to said body, and two one-piece sections stitched to the walls of the neck recess, and each including a lapel and a portion stitched at the shoulder seam, and extending to and stitched to the sleeves.

2. A sweater comprising a knitted body having its front formed with a neck recess provided with downwardly converging side edges, and two one-piece knitted lapels each stitched to a downwardly converging side edge of the neck recess and having two rows 50 of continuous knitting extending from the point of the lapel at angles to each other.

3. A sweater comprising a knitted body having its front formed with a neck recess, and two one-piece knitted lapels each stitched 55 to an edge of said recess and having two rows of continuous knitting extending from the point of the lapel at angles to each other.

4. A sweater comprising a knitted body, sleeves stitched to said body, the front of the 60 body having the neck recess extending laterally to the sleeves, and two one-piece lapels each stitched to an edge of the recess and having portions extending to and stitched to the sleeve and also secured to the back at the shoulder seam.

5. A sweater comprising a body, sleeves stitched to the body, the front of the body having a neck recess with lateral extensions between said front and the shoulder seam extending to the sleeves, and two one-piece lapels, each stitched to the neck recess and having a portion connecting the front of the body with the back at the shoulder seam and extending to and stitched to the sleeves.

6. A sweater comprising a body, sleeves 75 stitched to the body, the front of the body having a neck recess with lateral extensions between said front and the shoulder seam extending to the sleeves, and two one-piece sections stitched to the neck recess and each 80 including a lapel and a portion connecting the front of the body with the back at the shoulder seam and extending to and stitched to the sleeves, said sections being formed of knitted material with selvage edges extending 85 when the lapels are in closed positions vertically downward from the lapel point and horizontally outward from the point, the latter selvaged forming part of the shoulder seam.
